WILLIAM WILSON RUSSELL, OF TEPIC, MEXICO.

Letters Patent No. 86,695, dated February 9, 1869.

IMPROVEMENT IN SEWING-MACHINE FOR SEWING LEATHER.

The Schedule referred to in these Letters Patent and making part of the same.

To all whom it may concern:

Be it known that I, WILLIAM WILSON RUSSELL, of the city and canton of Tepic, State of Jalisco, Republic of Mexico, have invented an "Improved Machine for Stitching Leather;" and I do hereby declare that the following description and accompanying drawings are sufficient to enable any person skilled in the art or science to which it most nearly appertains, to make and use my said invention or improvement without further invention or experiment.

The object of my invention is to provide an improved machine for stitching leather, and other heavy, firm materials; and this I effect in part by the employment of an awl, which first pierces the leather for the passage of the needle.

This needle is passed into the same hole by an arrangement of cams, which produce a peculiar swinging motion of the head of the machine, and they may also be regulated so as to give a long or short stitch, as desired.

My improvement also consists in a peculiar movement of the hook or looper, which takes the thread from the needle and holds it until the needle leaves the leather, then advances and forms a loop for the awl, and retires as soon as the point of the awl passes the loop, so that the leather can be fed at the same time the thread is tightening around the awl.

The presser-foot is lifted at the instant of feeding the leather each time.

To more fully explain my invention, reference is had to the accompanying drawings, forming a part of this specification, of which—

Figure 1, sheet 1, is a side elevation of my machine, showing a section of a portion.

Figure 2, sheet 1, is a front-end view.

Figure 3, sheet 2, is another side view, showing the cams for swinging the head.

Figure 4, sheet 2, is an end view, showing the mechanism for operating the hook or looper.

Similar letters of reference in each of the figures indicate like parts.

A is a base-plate, which supports the mechanism, and which may be firmly fastened to a stand or table.

From this plate the bent arm B rises, and has the boxes C C fastened at the top.

The driving-shaft D turns in these boxes, and carries the bevelled-gear wheel E.

This wheel operates the combined bevel and spur-wheel F, which, in turn, drives the spur-wheel G. This wheel is made double, as shown in fig. 2, so as to have but one bearing, which is between the two parts of the wheel.

This device allows a crank-pin, a, to be placed on each side of the double wheel G, which, during its rotation, imparts a rectilinear motion to the vertical slides H and I, each of which has a transverse slotted head, J, in which the pin works, as shown.

The slide H carries the needle K, and the slide I carries the awl L, by which the leather is pierced for the passage of the needle.

The head M, in which work the double gear-wheel G and the two slides H and I, is pivoted on the regulating-screw N, and, at the opposite side, on a bearing, shown in dotted lines at O.

The whole head may thus swing back and forward in the direction of the line of stitching, so that the awl may first pierce a hole, and then, after it leaves the leather, the head swings forward to allow the needle to enter the hole.

To effect this swinging motion, two plates or cams, P and R, are placed on the back of the wheel F, these plates forming projections of different elevations.

An arm, S, is bolted to the swinging head, and carries, at its upper end, two loose rollers or wheels, T and U, which are moved back by the projections before mentioned, and thus swing the head.

The distance it moves, and the length of the stitch, are regulated by the size of the roller T, which may be easily changed when desired.

The hook or looper V, which forms the stitch, is keyed, or otherwise fastened, to the rock-shaft W, extending along the bottom plate, and having a crank, X, at the end.

This crank is connected with the lever Y by the rod Z.

The lever is operated by a cam, b, on the driving-shaft, shown clearly at fig. 4.

A collar, c, is fastened to the shaft W, and has an oblique slot, d, cut in it, into which the end of a guide, e, projects. This causes the shaft to slide forward at each partial rotation, carrying the hook V and the loop of the thread, so that as the awl pierces the leather, it also passes through this loop, and holds it after the hook recedes.

The spool of thread is mounted, as shown at f, and the thread passes from it through the lower part of the head M, and from thence through the end of an arm, g, which is pivoted at h, and is forced down by the hook i.

This hook is attached to the slide H, and, by forcing the arm down, leaves the thread loose and without tension when the needle passes through the leather, so that a loop may be readily formed.

A spring, k, raises the lever or arm g, when the needle-bar rises, and releases it, so that the thread again becomes tense as the stitch is being tightened.

A pin, m, on the needle-bar or slide, raises the presser-foot, by coming in contact with the bent arm n, just as the needle reaches its greatest elevation, and the leather is fed by the swinging of the head before the awl leaves the leather.

The operation of my machine is as follows:

As the awl approaches the leather, the roller T comes in contact with the projecting plate P, and swings the

head M back toward the line of stitching. The awl then passes through the leather, the needle rising at the same time, and, just at the end of its upward movement, raising the presser-foot, as before described. At this instant the roller U is forced out by the projection R, and swings the head still further, thus feeding the leather so far that when the head is moved to its forward position, the needle can enter the awl-hole in its next descent.

To form the stitch, the needle passes through the hole before mentioned, and as it rises, the thread being loose, a loop is formed. At the same instant the hook V is advanced by the mechanism before described, and takes the loop as the needle leaves the leather, and, by the traversing of the shaft, as already described, carries it forward, so that when the awl descends, it enters this loop, and holds it when the hook is withdrawn, in order that when the needle descends again, it may enter the loop at the same time that the awl is withdrawn, thus forming the stitch by linking each loop into the previous one, the thread being drawn around the awl by the arm g and spring k, so as to tighten the stitch just made, before the needle descends again to form a new one.

Having thus described my invention,

What I claim, and desire to secure by Letters Patent, is—

1. In combination with the swinging head M, the double wheel G, and the awl and needle-carrying arms H and I, substantially as described.
2. The combination, with the head M and arm S, provided with adjustable rollers, of the cams or plates P and R, substantially as described.
3. The combination of the hook V with the awl L, making a hole for the needle, for taking, carrying forward, and holding the loop until the needle descends through it to form a new one.
4. The combination of the awl L and needle K, when so arranged that the rising of the needle-holder lifts the presser, and the awl moves the material the length of a stitch, before withdrawing from the hole it has made, to give place to the needle, substantially as described.

In witness whereof, I have hereunto set my hand and seal.

WILLIAM WILSON RUSSELL. [L. S.]
